M. R. KESTER.
CAM HOLDER FRAME,
APPLICATION FILED MAR. 25, 1921.
1,416,959.

Patented May 23, 1922.

2 SHEETS—SHEET 2.

UNITED STATES PATENT OFFICE.

MALCOLM R. KESTER, OF CHICAGO, ILLINOIS.

CAM-HOLDER FRAME.

1,416,959.

Specification of Letters Patent. Patented May 23, 1922.

Application filed March 25, 1921. Serial No. 455,427.

To all whom it may concern:

Be it known that I, MALCOLM R. KESTER, a citizen of the United States, and resident of Chicago, in the county of Cook and State of Illinois, have invented certain new and useful Improvements in Cam-Holder Frames, of which the following is a specification.

My present invention has special reference to improvements on the construction of cam holder frame disclosed in my copending application filed November 22, 1920, Serial No. 425,863, which cam holder is especially designed for use in connection with passenger and freight elevator equipments and particularly to the installation or means for controlling the adjustment of the cam or cams that actuate the limit switches and the speed controlling or gradient switches in places where such switches constitute an integral part of the electrical devices and their connection with the elevator mechanism.

In the construction disclosed in my aforesaid application a cam holding bracket is provided that has vertical and lateral adjustment with respect to the elevator car on which the cam holder is supported, adjustable elements in the nature of anchor links being included and along which the cam holding bracket has longitudinal adjustment, the said links also having provision for effecting the shifting of the cam holding bracket laterally with respect to the car.

In the construction disclosed in the aforesaid copending application, provision is made for also adjustably securing the cam shoe or shoes upon the cam holding bracket.

My present invention primarily embodies certain improvements in the structural features of the type of cam holding frame disclosed in my copending application, and it seeks to provide for a more convenient manner or means for graduating and accomplishing the adjustment of the clamping element that holds the cam bracket to its different vertical and lateral adjustments to thereby accomplish any needed or desired adjustment of the cam holder frame bracket and its affixed cam or cam shoes from or toward the coordinating limit or switch roller.

Another object of my present invention is to provide a simple, inexpensive, easily controlled and effective means for bridging a gap between the cam shoes or member whereby to span the gaps occasioned or created by spreading apart, that is, more or less sepa-

rating the ends of a two-piece cam, the said bridging means providing for suitably and effectively conveying the "limits switch roller" across the aforesaid mentioned gap or opening.

With other objects in view, all of which will hereinafter be fully stated, my present invention embodies in a cam holder frame structure of the general character stated certain combination of elements and detailed arrangement of parts all of which will hereinafter be described, specifically mentioned in the appended claims and illustrated in the accompanying drawings, in which,

Figure 1 is a side elevation of a cam holder frame, of the type shown in my copending application, with my present improvements applied, so much of an elevator car being shown necessary to illustrate a practical application of my invention.

Figure 2 is an enlarged detail elevation of one half portion of the cam holder frame with an anchor link constructed in accordance with my present invention combined therewith.

Figure 3 is a horizontal section taken on the line 3—3 of Figure 2, the several parts being shown on a somewhat enlarged scale.

Figure 4 is a perspective view of the anchor link member hereinafter specifically mentioned.

Figure 5 is a longitudinal section of the cam holder frame or bracket member with my improved construction of connecting bridge or gap closure hereinafter fully explained.

Figure 6 is a perspective view of the U-shaped channel or bridge plate that constitutes a part of the said connecting bridge.

Figure 7 is a cross section thereof on the line 7—7 on Figure 5.

In the present presentation of my invention is shown an elevator cage which cooperates with the usual roller controls for the limit switches located above and below the travel of the said cage, it being understood that in my present construction of cam holder frame devices, the said devices are not restricted in their use to elevator apparatus but are intended for being practically applied, wherever found useful, that is, where cam shoes for engaging cut out switches or like make and break elements are required.

Referring more particularly to Figure 1, it will be noticed the holder frame is sup-

ported on one side of the car by what are termed "anchor links" 19 that sustain a cam carrying angle bar 1 upon which the cam shoe or shoes are adjustably mounted and which, in my present invention, cooperate with certain connecting bridge or gap closure means that constitutes an essential part of my said present invention.

In my copending construction, the anchor link 19 has a horizontal slot 24 through which passes a clamp or set screw for adjustable connection with an adjusting bolt which engages with the cam holding bracket member, before mentioned, and by which the said bracket also may be conveniently adjusted in vertical direction with respect to the anchor links 19 and the car.

Instead of using the bolt connections for effecting adjustment for the several parts stated, and as shown in the construction disclosed in my copending application, the adjustment of the bolt 25 in the horizontal direction through the long slot 24 in the anchor link 19 is effected in the manner best shown in Figure 2, by reference to which it will be observed that the end of the link 19, next to the cam shoe holding member 1, has an angled portion 31^a which constitutes the guide and bearing member for the threaded end of a screw bolt 28 that is formed with an eye 29 for engaging the clamp bolt 25 which passes through the long slot 24 in the anchor link 19, and the vertically elongated slot 4 in the leg 1 of the angle bar, whose other leg or member 10 carries the cam shoe or shoes, as shown.

A washer 23, on the bolt 25, is interposed between the eye 29 of the screw rod 28 and the anchor link 19, and a similar washer 23^a is also held on the bolt 25 between the eye 29 and a retainer strap 32, a third washer 23^b being located between the said strap 32 and the clamp nut 26 on the bolt 25, as shown.

Lock nuts 40—40 engage the threaded end of the screw bolt 28 and the adjacent faces of the apertured angle portion 31^a of the anchor link 19, as shown.

By reason of the peculiar arrangement of the adjusting bolt 28 and its connection with the bolt 25 that connects the angle bar shaped member 1 and the anchor link, as stated and shown, provides a simple, relatively inexpensive and easily adjusted means for permanently locking and securing the bolt 25 together with the holder frame, the angle bar and its affixed cam or cams in any desired position of horizontal adjustment throughout the length of the slot 24.

In my present construction of holder frame the shank end of the anchor link 19 has the bracket holes 19^a—19^a as in the other copending arrangement and it also has the same adjusting slot 24, the several stated parts being in substantially the same rela-

tive position and it is apparent that after the screw bolt 28 has been shifted to move the bolt 25 along the slot 24, with its attached parts to the desired position, the said bolt 28 can be held to the set position by screwing home the jam or lock nuts 40—40, as shown.

When an opposing pair of cam shoes 6—6 is used, as shown in Figure 5, and the said shoes adjusted along the face of the angle plate 10 of the bracket 1, by passing the cam bolts 60—60 through the shoe sections and the elongated slots 20—20 in the said angle face 10, the distance space between the adjacent ends of the shoes 6—6 is determined by the set of the said shoe members. In the arrangement of cam holder frame shown in my copending application, the distance space between the shoe sections is closed by a filler block that is fixedly attached to the adjacent ends of the said shoe sections.

In my present construction of cam holder frame the filler blocks are dispensed with and in lieu thereof a bridge connection between the shoe members is provided and the said connection, the construction and operative arrangement of which is best shown in Figures 5 and 7, consists of an elongated U-shaped member 5, of sheet steel, which, in practice, need not be more than one-sixteenth of an inch in thickness. The web or contact surface 50 of the member 5 is made to correspond with the contacting faces of the cam shoe section and to rest, at its opposite ends, flatwise upon the adjacent ends of the two shoe members, the opposite end flanges 51—51 lapping the said shoe section, the width between the flanges 51—51 being sufficiently more than that of the shoe sections to provide for a free telescoping of the shoes and the bridge connection when setting the latter to the desired adjustments.

The contact surface 50 of the U-shaped connection is suitably drilled to provide holes 52 at the opposite ends for receiving the countersunk screws 53 that attach the said ends to their respective shoe sections, the flanges 51 also having apertures for receiving screws 54 that thread into the opposite sides of the shoe sections.

7 designates a flat headed cap screw that passes through a central opening 11 in the flange 10 of the bracket 1, a spacer or filler block 75 being located under the top cap 5 and the flange 10 through which the screw 7 passes and other fastening screws 76 pass through the face 50, as is clearly shown in Figures 5 and 7.

In my present construction of cam holder frame after the adjustment has been made and set, the ends of the bridge connection can then be secured to their respective cam shoe sections and since the U-shaped member is formed of a very thin metal plate, the contacting face 50 thereof does not project

out from the exposed wood portions of the cam shoes far enough to over-actuate the coordinating switch roller or over-gap the opening or break in the switch transmission 5 terminals.

While I have shown and described the gap bridge or connecting member as flat and U-shaped in cross section, it is to be understood that the said gap bridge may 10 be made in any type, shape or design with any two oppositely disposed especially designed cam shoe sections.

From the foregoing description, taken in connection with the drawing, the complete 15 construction, the manner of the practical application of the several parts that constitute my present improvements on cam holder frames, and the advantages of my said improvements will be readily apparent 20 to those familiar with the installation of electric elevators and other like arts in which the electric cut out or make and break connection are in substantially constant active condition.

25 What I claim is:—

1. In an elevator installation of the character described, a frame attached to the elevator car, a switch engaging cam shoe carried on the said frame and means for effecting lateral adjustment of the frame and its attached shoe relatively to the elevator car, the said means including bracket arms attached to and projected from the car body, connections that join the cam shoe carrying frame with the said bracket arms and a screw feed device engaging each of the 30 said brackets and the cam carrying frame for effecting adjustment of the frame along the bracket and holding the frame to its 35 set adjustment.

2. In an elevator installation of the character described, in combination with the elevator car, a bracket arm fixedly attached to and extended laterally of the car, the said 40 arm having a longitudinal slot; of a frame, a switch engaging cam carried on the frame, a device including a clamp bolt that supports the cam carrying frame and which passes through the slot in the bracket and 45 is adapted for attaching the cam carrying frame to the bracket, and means mounted on the slotted bracket engaging the bolt clamp for effecting adjustment of the said bolt clamp and the cam frame supported 50 thereon along the bracket and for rigidly holding the bolt and the frame to their adjusted positions.

3. In an elevator installation of the character described, in combination with the elevator car, a bracket arm fixedly attached to and extended laterally of the car, the said 55 arm having a longitudinal slot; of a frame, a switch engaging cam carried on the frame, a device including a clamp bolt that supports the cam carrying frame and which

passes through the slot in the bracket and is adapted for attaching the cam carrying frame to the bracket, means adjustably mounted on the slotted bracket engaging the clamp for rigidly holding the bolt and the 70 frame to their adjusted positions, the said means including a screw bolt having an eye that engages the clamp bolt, a bearing on the slotted bracket for the screw bolt and clamp nuts engaging the bolt and the bracket 75 for securing the screw bolt, the clamp bolt, and the cam carrying frame to their shifted positions.

4. In an elevator installation of the character described, the combination with the 80 elevator car, anchor links connected to and projected from the car and laterally adjustable with respect to the car, each of the said anchor links having an elongated horizontal slot and an out-turned angled end provided 85 with an aperture; of a cam shoe carrying frame including an angled portion having elongated slots, a clamp screw bolt cooperative with each slot in the said angled portion of the cam carrying frame and with the elongated slot of corresponding ones of the anchor links, a screw eye bolt cooperative with each clamp screw bolt and with the aperture in the angled end of its respective anchor link, and clamp nuts engaging the eye bolt 95 screws, and their coengaging angled ends of the anchor links.

5. In an elevator installation of the character described, the combination with the car and bracket members movable with and projected laterally from the car; of a frame supported in vertical position on the bracket members, a pair of opposing cam sections, means for adjustably mounting the said sections along one face of the frame toward or 100 from each other and a gap closing element whose opposite ends engage the corresponding cam surface ends of the separated cam sections.

6. In an elevator installation of the character described, the combination with the car and bracket members movable with and projected laterally from the car; of a frame supported in vertical position on the bracket members, a pair of opposing cam sections, 110 means for adjustably mounting the said sections along one face of the frame toward or from each other, a gap closing element whose opposite ends engage the corresponding cam surface ends of the separated cam sections, 115 the said gap closing element consisting of a plate U-shaped in cross section whereby to lap onto the opposing separated ends of the cam sections and means for securing the U-shaped plate in position for bridging the gap 120 between the said ends of the cam sections.

7. In an elevator installation of the character described, the combination with the elevator car, bracket members projected laterally therefrom and a cam shoe holder frame

mounted on the bracket members, the said frame having oppositely disposed longitudinal slots; of a stay block fixedly secured to the holder frame midway its length, a U-shaped metal gap bridge fixedly attached to the stay block and projected in the direction of the length of the frame to each side of the stay block, a cam shoe section for each end

of the frame telescopically engaging the U-shaped gap bridge and a clamp bolt device 19 engaging each cam shoe section and the slot ways in their corresponding ends of the holder frame whereby to secure the cam shoe sections to their endwise supported adjustments.

MALCOLM R. KESTER.
